PLAY TENT FOR DRAPING OVER A BRIDGE
TABLE OR SIMILAR ARTICLE

Nora R. Lindsay, New York, N. Y.

Application December 30, 1955, Serial No. 39,528

Term of patent 14 years

(Cl. D34—15)

FIG. 2

FIG. 1

FIG. 3

FIG. 4

Fig. 1 is a front elevational view of a play tent for draping over a bridge table or similar article, showing my new design.

Fig. 2 is a top plan view thereof;

Fig. 3 is a side elevational view thereof, the opposite side having substantially the same appearance; and

Fig. 4 is a fragmentary rear view thereof, a part thereof being broken away.

The broken line showing of a bridge table is for illustrative purposes only.

I claim:

The ornamental design for a play tent for draping over a bridge table, or similar article, as shown and described.
